UNITED STATES PATENT OFFICE

JOHN B. TEESDALE AND CLYDE H. TEESDALE, OF GRAND RAPIDS, MICHIGAN, ASSIGNEES TO TEESDALE MANUFACTURING COMPANY, OF GRAND RAPIDS, MICHIGAN, A CORPORATION OF MICHIGAN

PUMP

Application filed May 29, 1930. Serial No. 457,227.

The present invention relates to pumps and more particularly to booster pumps.

The main objects of the invention are to provide a pump of the character above indicated having a float-operated valve for opening a conduit when the liquid within the container falls below the normal minimum level; to provide such a valve for opening a minimum liquid level conduit when the liquid within the container falls below the normal minimum level; to provide a pump of the character above indicated which is immersed in the oil within the container at all times except when the oil level therein falls below the normal minimum level and thus prevents suction of air through the pump; and generally to provide improved means of that character such as hereinafter appear.

An illustrative embodiment of the invention is shown in the accompanying drawing, wherein:

The figure is a front elevational view of the entire pump unit, certain portions being broken away to better illustrate the inside operating parts.

Referring to the drawing, the booster pump comprises a container 1 adapted to hold a liquid 2 such as fuel oil. The container has a cover plate 3 secured to its upper ends by suitable means such as screws 4.

Mounted on the upper side of this cover plate is an electric motor 5 within an electric circuit 6 whose shaft is connected to the shaft of a rotary pump 7 which supplies liquid to the container 1 through an intake conduit 8 connected to the supply pipe 9 which is provided with a check valve 10 of the spring and ball type. This conduit is connected to the pump which when operating draws oil there-through and exhausts it through the pump's outlet port 11 into the container 1.

A minimum liquid level conduit 12 is likewise connected to the pump 7 and its intake port extends below the vertically projecting outlet port 13 of the container to insure the obvious maintenance of a minimum liquid level therein.

A tiltable switch 14 of the mercury type and within the motor circuit 6 is operated by the float 15 which is limitedly slidably car-

ried on the vertically-disposed stem 16 between the stops 17, 18 thereon. The stem is pivotally secured at its upper end to the arm 19 which is connected to the switch 14 and the stem slidably passes through an aperture of the laterally projecting rod 20 intermediate its ends for maintaining the stem in a substantially vertical position. When the normal minimum level 21, which is normally maintained by the float-operated switch 14, falls below such level, a minimum level 22 is maintained within the container by the upwardly extending outlet port 13 of the container.

A minimum level float 23 is likewise secured to the stem 16 below the switch operating float 15 and when the liquid within the container thus falls below the normal minimum level 21 to the minimum level 22, the float 15 falls until it rests on the projecting rod 20 and the float 23 falls to the position shown contacting the pivotally mounted bell crank lever arm 24 which opens the valve 25. The pump 7 thus continues to pump liquid through the minimum level conduit 12 and exhausts it through the outlet port 11 of the pump instead of pumping air through the intake conduit 8 whose supply pipe is closed by the check valve 10. The motor and pump will thus continue to operate until manually shut off by a master switch, not shown, and the pump is therefore lubricated during this abnormal operation.

In operation, the motor driven pump 7 produces a suction in the intake conduit 8 which lifts the ball check valve 10 in the supply pipe 9 leading to the source of the liquid supply, not shown, and the liquid is expelled through the outlet port 11 of the pump into the container 1 faster than it flows therefrom through the container's outlet port 13. As the liquid level rises within the container 1, the float 15 continues to rise until it reaches the position shown in dotted lines where it abuts the stop 17 which tilts the switch 14 to shut off the motor 5 and its driven pump 7. As the liquid is withdrawn from the container 1, the float 15 falls and abuts the stop 18 which closes the tiltable mercury switch 14 to turn on the motor 5 to drive the pump 7.

In the event however that the source of liquid supply to the container 1 fails or is exhausted, the liquid within the container will fall from the normal minimum level 21 to the minimum level 22 controlled by the upwardly extending outlet port 13 of the container. As the liquid thus falls to the minimum level 22, the float 23 contacts the pivotally mounted bell crank lever 24 and its weight is sufficient to open the valve 25 permitting the pump 7 to draw the liquid remaining in the bottom of the container 1 and exhaust it through the outlet port 11 of the pump. The pump therefore will always continue to pump oil through the minimum level conduit rather than air.

The manually operable lever 26 secured to the arm 19 is provided to lift both floats when the source of liquid supply has been replenished thus permitting the unit to again renew its normal operation as soon as the normal minimum level 21 is regained within the container.

While but one specific embodiment of this invention has been herein shown and described, it will be understood that numerous details of the construction shown may be altered or omitted without departing from the spirit of this invention as defined by the following claims.

We claim:

1. In an organization of the class described, a container adapted to hold a liquid and having an outlet at the lower portion and provided thereat with means for maintaining a minimum liquid level within the container, a pump, a liquid intake supply conduit for said container connected to said pump, a minimum liquid level conduit connected to said pump and extending below the minimum liquid level, and a liquid level operated valve for selectively opening the minimum level conduit when the pump in its normal operation fails to draw liquid through the other conduit and the liquid within the container falls to the minimum level.

2. In an organization of the class described, a container adapted to hold a liquid therein at a normal minimum level and provided at the bottom with an outlet and having means thereat for maintaining a minimum liquid level within the container, an intake conduit for supplying liquid to the container, an electrically operated pump within an electric circuit for drawing liquid into said container through said conduit, an electric switch within said circuit, a float within said container operatively associated with the switch for opening said switch by the movement of the float in one direction and for closing the switch by movement of the float in the opposite direction to maintain the liquid normally within the tank between maximum and minimum levels, a minimum liquid level in-

let conduit connected to the pump for supplying liquid thereto and extending below the minimum level, and a liquid level operated valve for selectively opening the minimum liquid level inlet conduit when the liquid level within the container falls to the said minimum liquid level.

3. In an organization of the class described, a container adapted to hold a liquid and provided at the bottom with an outlet and having means thereat for maintaining a minimum liquid level within the container, an intake conduit for supplying liquid to the container, an electrically operated pump within an electric circuit for drawing liquid into said container through said conduit, an electric switch within said circuit, a float within said container operatively associated with the switch for opening said switch by the movement of the float in one direction and for closing the switch by movement of the float in the opposite direction to maintain the liquid normal within the tank between maximum and minimum levels, a minimum liquid level inlet conduit connected to the pump for supplying liquid thereto and extending below the minimum level, a valve normally closing the minimum liquid level inlet conduit, a second float, and means arranged in the path of the second float and operatively connected with said valve for causing the said second float to open the valve when the liquid within the container falls to the minimum liquid level.

4. In an organization of the class described, a container adapted to hold a liquid and provided at the bottom with an outlet and having means thereat for maintaining a minimum liquid level within the container, an intake conduit for supplying liquid to the container, an electrically operated pump within an electric circuit for drawing liquid into said container through said conduit, an electric switch within said circuit, a float within said container operatively associated with the switch for opening said switch by the movement of the float in one direction and for closing the switch by movement of the float in the opposite direction to maintain the liquid normal within the tank between maximum and minimum levels, a minimum liquid level inlet conduit connected to the pump for supplying liquid thereto and extending below the minimum level, a valve normally closing the minimum liquid level inlet conduit, a second float, and a lever operatively connected with the valve and arranged in the path of the said second float and adapted to be actuated by the same to open the valve when the liquid within the container falls to the minimum liquid level.

5. In an organization of the class described, a container adapted to hold a liquid and provided at the bottom with an outlet and having means thereat for maintaining

a minimum liquid level within the container, an intake conduit for supplying liquid to the container, an electrically operated pump within an electric circuit for drawing liquid into said container through said conduit, an electric switch within said circuit, a float within said container operatively associated with the switch for opening said switch by the movement of the float in one direction and for closing the switch by movement of the float in the opposite direction to maintain the liquid normally within the tank between maximum and minimum levels, a minimum liquid level inlet conduit connected to the pump for supplying liquid thereto and extending below the minimum level, a valve normally closing the minimum liquid level inlet conduit, a second float, a lever operatively connected with the valve and arranged in the path of the said second float and adapted to be actuated by the same to open the valve when the liquid within the container falls to the minimum liquid level, a single stem operatively associated with both floats, and a manually operable lever connected with the said stem for lifting the floats for readjusting the operating function of the pump.

In testimony whereof we JOHN B. TEESDALE and CLYDE H. TEESDALE, have hereunto set our hands at Grand Rapids, Michigan, this 24th day of May, 1930, and at Chicago, Illinois, this 26th day of May, 1930, respectively.

CLYDE H. TEESDALE.
JOHN B. TEESDALE.
